United States Patent Office

Des. 184,567
Patented Mar. 10, 1959

184,567

DISPENSER FOR CONDIMENTS, OR SIMILAR ARTICLE

Henry C. Keck and Burnie M. Craig, Pasadena, and
Thomas K. Hale, Glendale, Calif., assignors to Dispensers, Inc., Los Angeles, Calif., a corporation of California

Application July 15, 1957, Serial No. 46,935

Term of patent 14 years

(Cl. D44—22)

Fig. 1.

Fig. 2.

Fig. 1 is a perspective view of a dispenser for condiments embodying our new design; and

Fig. 2 is a top plan view thereof.

The dominant features of our new design are shown in solid lines in the drawing.

We claim:

The ornamental design for a dispenser for condiments, or similar article, substantially as shown and described.
